UNITED STATES PATENT OFFICE

ISAAC MITCHELL WHERRY, OF ZEARING, IOWA

INTERNAL COMBUSTION ENGINE

Application filed October 17, 1929. Serial No. 400,309.

This invention relates to internal combustion engines and more particularly to devices of this character of the double acting two cycle type and has, for one of its objects, to provide in a manner as hereinafter set forth, an engine of the aforementioned character wherein coating power and charge compressing cylinders are associated with each other in such a manner that the combustion charge will be highly compressed in the compressing cylinder prior to its passage into the power cylinder.

Another important object of the invention is to provide, in a manner as hereinafter set forth, an engine of the aforementioned character having valves associated therewith for exhausting the burned charge from the power cylinder prior to the entrance of the new charge thereto, thus preventing the mixing of the incoming and outgoing gases and preventing waste of the former and wherein pairs of simultaneously operated valves are positioned in the passages between the compressing cylinder and the power cylinder for permitting the passage of the gas therethrough during only certain portions of the stroke of the power piston.

Other objects of the invention are to provide, in a manner as hereinafter set forth, an internal combustion engine of the aforementioned character which will be simple in construction, strong, durable, efficient in its use and which may be manufactured at a low cost.

Other objects and advantages of the invention will become apparent from a study of the following specification, taken in connection with the accompanying drawings wherein like characters of reference designate corresponding parts throughout the several views, and wherein:

Figure 1 is a side elevation of an internal combustion engine constructed in accordance with this invention,

Figure 2 is a horizontal sectional view taken approximately on the line 2—2 of Figure 1,

Figure 3 is a cross section taken approximately on the line 3—3 of Figure 2, and looking in the direction of the arrows,

Figure 4 is a vertical cross section taken

approximately on the line 4—4 of Figure 2 and looking in the direction of the arrows,

Figure 5 is a detail view in perspective showing one of the rods for actuating the forward valves,

Figure 6 is a cross section through the crank shaft showing one of the cams thereon and the adjacent portion of a valve rod in engagement therewith.

Referring to the drawings in detail, the reference character 1 designates a base upon which is mounted, adjacent one end, the vertical standard 2 and journaled on the standard 2 is a crank shaft 3 having a fly wheel 4 on one end. A horizontally disposed power cylinder is mounted adjacent the opposite end of the base 1 in spaced relation to the standard 2 and is designated generally by the reference character 5.

Adjacent the power cylinder 5 and parallel therewith is a compressor cylinder which is designated generally by the reference character 6. Pistons 7 and 8 are mounted for simultaneous reciprocation in respective cylinders 5 and 6 through the medium of the rods 9 and 10 and the connecting rods 11 and 12 coupled to the crank shaft 3, as will be quite obvious.

As seen most clearly in Figures 3 and 4 of the drawing, the cylinders 5 and 6 are preferably integrally connected together in parallel spaced relation and are provided, on their opposite ends with removable heads 13 and 14, each of which covers the adjacent end of both of the cylinders. As seen in Figure 2 of the drawings, the head 14 is provided with packing 15 through which the rods 9 and 10 move. Intake valves 16 and 17 are mounted at opposite ends of the compressor cylinder 6 and controls communication of said cylinder with a source of fuel supply through the conduit 18. Outlet valves 19 and 20 are also provided for the cylinder 6 at its opposite end. The power cylinder 5 is provided with inlet valves 21 and 22 at its opposite end and adapted for communication with the valves 19 and 20 and the power cylinder is further provided with the exhaust valves 23 and 24.

All of the aforementioned valves are nor-

mally maintained in closed position through the medium of the coil springs 25 which encircle the free end portion of the stem and impinge the adjacent surfaces of the cylinders 5 and 6 from which said stem projects and a washer or shoulder 26 adjacent said free ends of the stem, the valves 16, 17, 23 and 24 are opened through the medium of the rods 27 having one end in engagement 10 with the free end of the valve stem and the opposite end in engagement with cam 28 on the crank shaft 3.

The valves 19, 20, 21 and 22 are simultaneously operated through the medium of the 15 rod 29 having cross heads 30 thereon for engagement with the stems of the adjacent pairs of said valves. The opposite ends of the rods 29 are engaged with the cams 31 on the crank shaft 3.

20 Guides 32 are provided on the base 1 and on the cylinders 5 and 6 for the valve rods. Spark plugs 33 are threaded into the opposite end of the power cylinder 5.

In the operation of the engine, the crank 25 shaft 3 is rotated and the pistons 7 and 8 reciprocate in the cylinders 5 and 6. With the pistons in the position shown in Figure 2 of the drawings, a charge has been compressed in the outer end of the power cylinder 5 and is ignited through the medium of the spark plug 33 and the piston 7 is driven inwardly.

At the same time the piston 8 also moves inwardly in the cylinder 6 and the valve 16 35 is caused to open and a charge of fuel is drawn into that end of said cylinder. As this stroke of the piston 8 commences the valve 17 is closed and the charge which is in the inner end of the cylinder is compressed therein by piston 8.

As the power piston 7 starts its inward stroke, the exhaust valve 24 opens and remains opened until practically all of the exhaust gases in that end of the power cylinder 45 5 have passed therethrough at which time said valve closes. It will be here stated that the cams 28 which operate the exhaust valves 24 and 23 are adapted to maintain said valves in open position only during a portion of the 50 outward and inward stroke of the piston 7. When the valve 24 closes, the valves 20 and 22 are opened simultaneously and the fuel charge which has been compressed in the inner end of the cylinder 6 is forced into the 55 inner end of the power cylinder 5.

As the piston 7 approaches the end of its inward stroke the valves 20 and 22 close and further movement of the piston serves to further compress the gas trapped therein and 60 when said piston has reached the limit of its inward movement or very nearly, the compressed charge is ignited through the medium of the spark plug 33 in that end of the cylinder.

65 The pistons 7 and 8 then start the outward

stroke and the valve 23 is opened to exhaust the gas from the outer end of the cylinder. Simultaneously the valve 16 is closed and the valve 17 is opened. The piston 8 now compresses the charge which has entered the 70 outer end of the cylinder 6 through the valve 16 and a charge is drawn in through the valve 17. The valve 23 closes before the piston 7 reaches the limit of its outward movement and immediately thereafter the valve 19 and 75 21 open to permit the compressed charge from the outer end of the cylinder 6 into the corresponding end of the power cylinder 5.

The valves 19 and 21 then close and the 80 continued outward movement of the piston 7 further compresses the charge until said piston reaches the end of its outward movement, or nearly so, at which time the spark plug 33 in that end of the cylinder ignites 85 the charge.

As will be seen in Figure 2 of the drawings, the heads 13 and 14 are constructed to provide combustion chambers 35 at opposite ends of the power cylinder 5 while the portions thereof which close the opposite end of the compressor cylinder 6 are constructed to provide very little space between their inner walls and the opposed wall of the piston 8 when said piston is at that end of the cylinder. 90

This is for the purpose of discharging nearly all of the compressed gases into the power cylinder. As seen in Figure 5 of the drawing, certain of the valve rods 27 are provided with offset intermediate portions 27' 100 to permit same to pass portions of the engine which are between the crank shaft 3 and the valve which these rods operate.

While an engine of the horizontal type and embodying a single power cylinder and a single compressor cylinder has been shown in the drawings forming a part of this application, it is to be understood that the invention contemplates the provision of any desired number of cylinders which may be disposed in any position, such as in a vertical or in an inclined position. 105

It is believed that many advantages of an internal combustion engine constructed in accordance with this invention will be readily understood, and although the preferred form of the invention is as illustrated and described, it is to be understood that changes in the details of construction may be had which will fall within the scope of the invention as claimed. 115

Having thus described my invention, what is claimed as new is:

1. An internal combustion engine of the character described comprising a power cylinder having inlet and outlet ports at its opposite ends, a compressor cylinder having inlet and outlet ports at its opposite ends, the outlet ports thereof communicating with the inlet ports of the power cylinder, pistons 125 130

mounted for simultaneous reciprocation in the cylinders, valves in the inlet ports of the compressor cylinder for admitting a fuel charge thereto, valves in the outlet ports of 5 the power cylinder for exhausting gases therefrom and simultaneously operated pairs of valves in the communicating inlet ports of the power cylinder and the outlet port of the compressor cylinder for the passage of 10 the fuel discharge from said compressor cylinder into the power cylinder.

2. An internal combustion engine of the character described comprising a power cylinder having inlet and outlet ports at its 15 opposite ends, a compressor cylinder having inlet and outlet ports at its opposite ends, the outlet ports thereof communicating with the inlet ports of the power cylinder, pistons mounted for simultaneous reciprocation 20 in the cylinders, valves in the inlet ports of the compressor cylinder for admitting a fuel charge thereto throughout the strokes of the piston therein, valves in the outlet ports of the power cylinder for exhausting gases 25 therefrom throughout portions only of the strokes of the piston therein and simultaneously operated pairs of valves in the communicating inlet ports of the power cylinder and the outlet 30 ports of the compressor cylinder for the passage of the fuel charge from said compressor cylinder to said power cylinder while the piston in the latter cylinder is traversing the portions of its stroke at which the valve in the outlet ports thereof 35 are closed.

3. An internal combustion engine of the character described comprising a power cylinder having inlet and outlet ports at its opposite ends, a compressor cylinder having 40 inlet and outlet ports at its opposite ends, the outlet ports thereof communicating with the inlet ports of the power cylinder, pistons mounted for simultaneous reciprocation in the cylinders, valves in the inlet ports of the 45 compressor cylinder for admitting a fuel charge thereto throughout the strokes of the piston therein, valves in the outlet ports of the power cylinder for exhausting gases therefrom throughout portions only of the 50 strokes of the piston therein and simultaneously operated pairs of valves in the communicating inlet ports of the power cylinder and the outlet ports of the compressor cylinder for the passage of the fuel charge 55 from said compressor cylinder to said power cylinder while the piston in the latter cylinder is traversing portions of its strokes at which the valves in the outlet ports thereof are closed, independent means for actuating 60 the valves of the outlet ports of the power cylinder and the inlet ports of the compressor cylinder and common means for actuating each pair of the simultaneously operated valves.

65 4. An internal combustion engine of the

character described comprising a power cylinder having inlet and outlet ports at its opposite ends, a compressor cylinder having inlet and outlet ports at its opposite ends, the outlet ports thereof communicating with the inlet ports of the power cylinder, pistons mounted for reciprocation in the cylinders, a crank shaft coupled to the pistons to cause simultaneous movement thereof in the cylinders, cams mounted on said crank shaft, 70 valves in the inlet ports of the compressor cylinder for admitting a fuel charge thereto throughout the strokes of the piston therein, valves in the outlet ports of the power cylinder for exhausting gases therefrom throughout portions only of the strokes of the piston therein and simultaneously operated pairs of valves in the communicating inlet ports of the power cylinder and the outlet 75 port of the compressor cylinder for the passage of the fuel charge from said compressor cylinder to said power cylinder while the piston in the latter cylinder is traversing the portions of its strokes at which the valves in the outlet ports thereof are closed, and means 80 for actuating the valves comprising independent reciprocating rods engaged at one end with certain of the cams on the crank shaft and at their opposite ends with the inlet and outlet valve of the compressor and power cylinder respectively and reciprocating rods each having one end engaged with one of the remaining cams on the crank shaft and having heads on their opposite ends engaged with the pairs of valves in the communicating outlet and inlet ports of the compressor and power cylinders respectively. 85

In testimony whereof I affix my signature.
